DISPENSING CABINET

William B. Meglitz, Berlin, N. H., assignor, by
mesne assignments, to Reconstruction Finance
Corporation, Washington, D. C., a corporation
of the United States of America

Application September 23, 1939, Serial No. 296,237

1 Claim. (Cl. 242—55.5)

This invention relates to a cabinet for dispensing strip material such as paper from a roll of the material which is inserted within the cabinet. While it can be used for paper strips of various kinds, the cabinet shown in the drawings is especially designed for dispensing paper toweling such as supplied in rolls.

It is an object of the invention to provide a dispensing cabinet adapted to contain a roll of such paper toweling and to facilitate the grasping of the cut end of the strip so that a desired length of paper can be withdrawn from the cabinet for use. It is a further object of the invention to facilitate the severing of the withdrawn portion from the portion of the strip which remains in the cabinet. It is a further object of the invention to provide a cabinet so constructed that the paper will feed out of the cabinet easily regardless of how much has been previously withdrawn from the roll.

Various other advantageous features will be apparent from the following description of an embodiment of the invention, and from the drawing of which

Figure 1 is a perspective view of a cabinet embodying the invention.

Figure 2 is a transverse section of the cabinet taken on a vertical plane.

Figure 3 is a perspective view of the cutter blade for severing the strip.

Figure 4 is a fragmentary sectional view on the line 4—4 of Figure 2.

Figure 5 is a fragmentary portion of the view shown in Figure 2, illustrating how the cabinet is used.

As indicated in Figure 1, the cabinet may be provided with side walls 10 and 12, a rear wall 14 and a bottom 16. A suitable cover 20 is hinged to the cabinet, as at 22, and is preferably curved forward and downward so that it forms a top and front wall therefor. The forward portions of the side walls 10 and 12 are shaped correspondingly and the cover 20 is preferably provided with side flanges 24 which stiffen the cover and which overlap marginal portions of the side walls. As shown, the cover 20 does not extend all of the way down to the forward edge of the bottom 16 but is spaced a substantial distance above such edge, thus leaving an opening 30 in the front of the box. This opening is normally closed by a cutter blade 32, a portion of which at least is movable inward to facilitate grasping the cut end of the paper strip contained in the cabinet as hereinafter described. In the embodiment of the invention shown in the drawing, the

entire blade 32 is swingable inward, the blade being pivoted at its upper corners, as at 34, to the side walls 10 and 12 of the cabinet. The blade is rockable about its upper edge as an axis and normally hangs in a vertical plane substantially flush with the free forward edge 36 of the bottom 16, thus serving as a portion of the front wall of the cabinet. A pair of suitable stop elements or lugs 38 project from the side walls in front of the blade 32 so as to prevent rocking movement of such blade forward or outward from its vertical position. The blade 32 can be suspended in such a manner as to hang vertically by its own weight or with the help of an additional weight suitably arranged with respect to its rocking axis. As shown, a light spring 40 is provided to bear against the rear face of the blade so as to press it against the stop lugs 38 and to oppose resiliently inward swinging movement of the blade. A spring 40 may be provided, if desired, at each end of the blade.

A guiding member 42 is mounted within the cabinet and includes a flat lower portion 44 which is spaced slightly above the forward portion of the substantially horizontal bottom 16, as indicated in Figures 2 and 5, so as to form a narrow substantially horizontal guiding passage for the strip of paper as it leaves the roll and issues from the container. The lower portion 44 of the guide member is preferably inclined slightly with reference to the substantially horizontal bottom so that the guiding passage progressively narrows toward its forward orifice. The guide member 42 may be conveniently supported by a pair 30 of tabs 46 which are secured by any suitable means to the side walls of the cabinet, leaving the narrow guiding passage unobstructed. The upper portion of the guide member is bent back from the lower portion, as at 48, thus forming a flared orifice at the rear of the guide passage to facilitate threading the paper strip into the passage. As shown in Figure 2, the forward edge 50 of the guide plate 44 is offset rearwardly from the forward edge 36 of the bottom 16 and is 40 slightly below and to the rear of the bottom edge of the cutter blade 32 when the latter is in its normal vertical position. The forward portions of the bottom 16 and the guide member 44 are recessed, as at 54, so as to expose a portion of the cut end of the paper strip which is usually flush with the forward edges of the bottom 16 and the guide plate 44. Thus the thumb and fore finger of the user may conveniently grasp such exposed portion of the strip by pushing the cutter blade 32 so as to swing it back as indicated in Figure 5.

Instead of having the whole cutter blade arranged to swing inward, the end portions may be fixed and the central portion adjacent to the recesses 54 may be mounted so as to swing inward to facilitate grasping the portion of the cut end of the paper strip exposed by the recesses.

The guide plate 44 also acts with the bottom 16 as a braking element or deterrent tending to prevent the cut end of the strip from being pushed back into the cabinet and thus out of the recess 54 by the inherent springy quality of the paper and its natural curl acquired from its rolled condition. This tendency of the paper to curl after having been in a rolled condition results in the cut end portion of the paper bearing against the bottom 16 and the guide member 44 in several places, as indicated in Figure 2, this resulting in a sufficient frictional drag to prevent retraction of the paper from the recess 54.

To facilitate severing a withdrawn portion of the strip, the lower edge of the cutter blade 32 is formed with two groups of serrations 60, these groups being on either side of a central straight edge portion 62 and extending to the ends of the blade. The serrations of each group are preferably inclined toward the adjacent end of the blade so that the serrations will more positively catch on the paper strip as the withdrawn portion is pulled upward to sever it from the portion remaining in the cabinet. The straight edge portion 62 is of sufficient length to span the recess 54 and is directly opposite or above such recess, as best appears in Fig. 1. Thus the fingers of the operator will not encounter serrations when the blade is swung back to permit gripping of the cut end in the recess 54.

The side walls 10 and 12 of the cabinet are provided with opposed vertical channels 66 and 68 which are of sufficient width to receive the

ends of the arbor which extends through the paper roll. The roll is intended to rest upon the bottom of the cabinet so that the paper feeds tangentially therefrom directly into the guide passage through which it issues from the cabinet. As the roll decreases in size with the removal of paper therefrom, the ends of the arbor descend in the grooves 66 and 68. The grooves, however, prevent the roll from being pulled into a diagonal position within the cabinet and thus ensure proper feeding of the strip through the guide passage.

It is evident that various modifications and changes may be made in the embodiment of the invention illustrated and described without departing from the spirit or scope thereof as set forth in the following claim.

I claim:

In a cabinet of the character described for dispensing paper from a roll rotatably mounted therein, said cabinet having front and rear walls, end walls and a bottom; a cutter blade extending substantially entirely across the front of said cabinet and having a lower cutting edge defining with the bottom of said box a slot through which the paper is dispensed, said blade being pivotally mounted at the upper part thereof to swing inwardly of the cabinet to provide grasping access to said paper, stop means to prevent said blade from swinging outwardly of the cabinet, and a recess in the bottom of said cabinet to provide a finger grip on said paper, said lower edge of the cutter blade having a straight edge portion in substantial registry with said recess which straight edge portion has a length at least substantially equal to the width of said recess, the remaining portion of said lower edge being serrated.

WILLIAM B. MEGLITZ.
